RIDER AND DRUM FOR LITHOGRAPHIC PRESSES

Filed Dec. 31, 1926

Inventor

THOMAS C. GOWANS:

By His Attorney

Richard D. Dow

Patented June 25, 1929.

UNITED STATES PATENT OFFICE.

THOMAS C. GOWANS, OF BROOKLYN, NEW YORK.

RIDER AND DRUM FOR LITHOGRAPHIC PRESSES.

Application filed December 31, 1928. Serial No. 158,302.

This invention relates to lithographic offset presses and in particular to the riders and oscillating drums used therein.

Since the advent of lithographic offset presses using the soft rubber rollers, technically known as form rollers, a condition has arisen whereby the riders and drums (oscillating and otherwise), become stripped of their ink, it of course being understood that the function of these riders and drums is to carry the ink to the form rollers, which engage the form which does the lithographing. In the use of these lithographing plates, water is a necessary element and during its use, a grease-resisting film is formed on the riders and drums by the action of the water from the plate and form rollers. As the art of lithography is based on the resistance of this film to take ink while damp, it will be readily seen that a difficult proposition confronts the operator of the press in order to make the riders and drums retain their ink. The film of water is purposely created on the lithographic metal plates, so that it will resist the ink but this water gets to the form rollers and consequently to the riders and drums with the result that they will not transfer the ink properly. An expedient is the original corrosion of the drums and riders made of metal so that water thereon will not effect the rough surface thereof to resist the spreading of ink over the riders and drums during the latter's oscillation, it being of course understood that the oscillation and revolving movement of the drums spread the ink evenly over the intermediate roll from which it is transferred to the riders and hence from the form rollers to that portion of the lithographic plate meant to receive it, but this corrosion by artificial means, soon becomes sufficiently smooth so that the water effects the same and the result is that it will not take the ink. This is called stripping and of course necessitates stopping the press during the work, which is not only a great loss of time but additional expense in removing the drums for reconditioning so that they will take ink.

A particular object of my invention, therefore, is to provide a drum or rider for a lithographic offset press, which will overcome this condition and which need not be reconditioned at any time in order that it will properly transfer the ink.

A further object of my invention is to provide a particular type of drum or rider around

which can be moulded a sleeve, which, when worn can be removed from the form or core and another sleeve moulded thereon which can be made up at small cost and used over a long period of time in a press without recovering.

A still further object of the invention is to provide a cover of hard rubber or vulcanite which can be moulded on to the core of the riders and drums and which will be so arranged as to withstand the side thrust and rotary friction of the drums and riders against their adjacent rollers.

To enable others skilled in the art to fully comprehend the underlying features of my invention that they may embody the same in the various modifications in structure and relation contemplated, a drawing depicting a preferred form has been annexed as a part of this disclosure and in such drawing, similar reference characters denote corresponding parts throughout all the views, of which,

Figure 1 is a fragmentary view in sectional elevation showing the arrangement of the oscillating drum and rider and the intermediate rollers as used in the ordinary form of lithographic offset press.

Figure 2 is an enlarged, top plan view of an oscillating drum, a portion thereof being shown in section, the same being covered with my improved coating or sleeve of hard rubber or vulcanite.

Figure 3 is a sectional view taken on the line 3—3 of Figure 2, the same being shown broken for compactness of illustration and showing in cross section the arrangement of the parts necessary in the manipulation of the oscillating drums, and

Figure 4 is a sectional view taken on the line 4—4 of Figure 3 showing the method of driving said oscillating drum.

Referring to the drawings in detail, 5 indicates a press frame of any particular type, having pivoted therein the ink roller 6 which operates in the cut-out bottom of an ink reservoir 7, the ink being transferred from said ink roller 6 to the adjacent oscillating drum 8 through the medium of a movable roller 9 which moves back and forth from contact with roller 6 to contact with drum 8. The drum 8, of course, is separated from the rider 10 through the medium of an intermediate roller 11 and the rider 10 is separated from the cylinder by a form roller 12. These rollers 11 and 12 are made of soft rubber so that they

100

110

will carry the ink but in order to provide the intermediate stiff rollers or oscillating drums and riders, as they may be termed, and are termed in the art, it is necessary that they be 5 coated with a rigid material so that they can be moved longitudinally to evenly distribute the ink on the form rollers.

In experimenting with different substances with which to coat or make the drums or riders, I found that only metal will take the ink resisting film while hard rubber or vulcanite, celluloid or bakelite and even enamel and paint offers resistance to this ink resisting film. I did find, however, that hard rubber 10 and vulcanite have the greatest resistance and have therefore adopted the hard rubber as the covering for the oscillating drums and riders which are disposed adjacent the form rollers. When the leather covered form rollers were 15 in use, the transfer of this ink resisting film was not so pronounced but since the composition and rubber form rollers are in general use, that is the soft rubber rollers, the condition is very noticeable.

20 As embodied in the press, the oscillating drums are carried on a spindle 13 which is held at its end in the frame 5 of the press and on this spindle 13, is mounted the oscillating sleeve 14 which carries at one end, a driven 25 gear 15 which is constantly in mesh with an elongated driving gear 16, the driving gear 16 being positioned upon a jack shaft 17 held in frame pieces and operated through the medium of the driving sprocket 18, the opposite end of the sleeve 14 carries a slotted collar 19, which is engaged by the oscillating arm 20, it being evident that the oscillating of the arm 20 causes movement of the sleeve 14 longitudinally of the spindle 13, 30 while the same is being driven through the medium of the driving gear 16. The sleeve carries at its intermediate portion, the drum or rider core 21 which may be made of metal, wood, or other rigid material, the face thereof 35 of being grooved as at 22 so that the hard rubber sleeve 23, when moulded thereon will engage in said slot or groove 22 and prevent longitudinal movement of said sleeve 23 relatively to the cores 21 when the sleeve 14 is 40 given an oscillatory movement lengthwise of the shaft or spindle 13. This oscillatory movement is imparted to the drum or rider so that the ink will be evenly distributed on the

form rollers and the revolving motion of the drum or rider is taken care of through the 55 medium of the gear 15 and its driving member 16.

It is to be distinctly understood that the groove 22 in the core 21 may be circumferential and spaced one from another depending 60 upon the diameter of the core or the groove 22 may be one continuous spiral cut in the periphery of the core 21 and may be of any depth desired, into which the sleeve 23 may be cast so that the same will be held securely on 65 said core 21.

It is evident, therefore, that I have provided an improved oscillating drum and rider construction to be used in lithographic offset presses which will resist the ink resisting 70 film and will at all times carry a surface which will efficiently hold ink transferred thereto by the adjacent rollers.

It is evident, also that I have provided an oscillating drum or rider which does not 75 have to be continually reconditioned so that it will carry the ink on its surface and also one which will have a minimum of wear and which can be made up at a relatively smaller cost than the reconditioning process to which 80 the drums or riders would otherwise have to be subjected to as they must be in the present practice.

While I have illustrated and described my invention with some degree of particularity, 85 I realize that in practice various alterations therein may be made. I therefore reserve the right and privilege of changing the form of the details of construction or otherwise altering the arrangement of the correlated parts 90 without departing from the spirit of the invention or the scope of the appended claim.

Having thus described my invention what I claim as new and desire to secure by United States Letters Patent is;—

95 An ink transfer drum arranged for revolving and oscillatory movement comprising a spindle, a sleeve on the spindle movable longitudinally thereof, a core on said sleeve made of rigid material and having a spiral groove 100 of substantially rectangular cross section cut in the face thereof and a sleeve of hard rubber moulded on the periphery of the core and in the groove.

In testimony whereof I affix my signature,
THOMAS C. GOWANS. [L. S.]
